A. ISAACS.

SPINDLE FOR DUPLICATING MACHINES AND THE LIKE.
APPLICATION FILED OCT. 4, 1917. RENEWED FEB. 18, 1921.

1,377,584.

Patented May 10, 1921.

Albert I. Isaacs Inventor
By his Attorney
Edmond Congdon Brown

UNITED STATES PATENT OFFICE.

ALBERT ISAACS, OF NEW YORK, N. Y., ASSIGNOR TO BECK DUPLICATOR COMPANY,
A CORPORATION OF NEW YORK.

SPINDLE FOR DUPLICATING-MACHINES AND THE LIKE.

1,377,584.

Specification of Letters Patent. Patented May 10, 1921.

Application filed October 4, 1917, Serial No. 194,822. Renewed February 18, 1921. Serial No. 446,107.

To all whom it may concern:

Be it known that I, ALBERT ISAACS, a citizen of the United States, and a resident of the borough of Queens, in the city and 5 State of New York, have invented certain new and useful Improvements in Spindles for Duplicating-Machines and the like, of which the following is a specification.

The invention relates to spindles or rollers, more particularly such as are adapted to bear rolled or stored thereupon a duplicating medium such as is employed with duplicators; and has for one of its principal objects to provide such a roller which may 10 be easily and conveniently employed in connection with various styles of duplicators now known in the art and which may be easily and quickly removed and replaced in a reversed position as hereinafter particularly explained.

The invention consists in the novel construction, arrangement and combination of elements and parts, as shown in the accompanying drawings and hereinafter more particularly described.

In the said drawings, Figure 1 is a side view of one form of my improved spindle, the same being broken away at its central portion; Fig. 2 is a longitudinal section of 30 the same; Figs. 3 and 4 are detail views to be hereinafter described; Fig. 5 is an end view; Fig. 6 is a side view of the same, showing one manner of securing the same to a duplicator; and Fig. 7 is a fragmentary 35 view showing a modified form of supporting means for said roller.

In carrying my invention into effect in the embodiment thereof which I have selected for illustration in the accompanying 40 drawings and description in this specification I provide a tube 11 of wood or other suitable material, open at both ends. A rod 12 is also provided, adapted to slide in the said tube 11, the main portion of which rod 45 12 is somewhat shorter than the tube 11. The rod 12 is, however, provided at each end with a longitudinal projection 20, of smaller diameter than the said rod 12, the outer end of each of said projections 20 being provided with a further longitudinal projection or pin 19.

I provide disks 13, (see Fig. 3) of metal or the like, adapted to fit over the ends of the tube 11. These disks are slightly larger 55 in diameter than the tube 11; but each disk

is recessed as shown at 14, at various points on its periphery, the faces of these recesses being flush with the outside of the tube 11 when the disks 13 are in place. At the center of each disk 13 I provide a square perforation 15.

I provide caps 16 stamped out of sheet metal or the like, the form of which is particularly shown in Fig. 4, and which are adapted to fit over the disks 13, and secure 60 them in place over the tube 11. Each of these caps 16 is provided with a central square perforation 18 adapted to coincide with the perforations 15 when the disks 13 and caps 16 are in place; and is also provided with securing members 17, adapted to be bent inward over the disks 13, to pass through the recesses 14, and along a portion of the tube 11, to which they may be secured by means of screws or tacks 22, passing 65 through suitable perforations 21 therein, and into the material of the tube 11.

In duplicating machines of the types with which my improved spindle is adapted to be used, it is desirable to provide a suitable 80 frame, comprising upright portions, such as those designated 23 and 24 in Fig. 6, between which the spindles carrying the duplicating medium are adapted to be journaled. Any suitable means for securing the roller 85 or spindle in place may be provided, but for the purpose of illustration I have shown the member 23 provided with a slot, indicated at 25 by dotted lines (see Fig. 6) and on the outside of the member 23 I show a downwardly extending spring strip 26 secured at 27 to the member 23 above the slot 25, this strip 26 being provided at its lower end with a perforation adapted to receive the outer end of the pins 19. Journaled in the 90 member 24 I have shown a crank 28, provided, as is usual in such constructions, with a ratchet 29 having a pawl 30 adapted to engage therewith. On the inner side of the member, and connected with the crank 95 28, is a square chuck member adapted to fit into the openings 18 and 15. This chuck member is designated 31, and is shown in dotted lines in Fig. 6.

In use, either end of the spindle may be 105 inserted over the chuck 31, which enters the spindle through the perforation 18, and bears against the end of the pin 19, which it forces into the interior of the tube 11, thus forcing the portion 20 at the opposite 110

end of the rod 12 outward into the perforations 15 and 18, so that the pin 19 at said opposite end will project from the tube 11. In placing the end of the spindle over the 5 chuck 31, the spindle is so held that when the pin 19 at the opposite end is pushed out, it will project into the slot 25 in the member 23. The end of the pin 19 may then be easily slipped into the perforation in the 10 lower end of the spring 26, the portion of the member 23 above the opening 25 holding the spindle from slipping off the chuck 31.

In the modification shown in Fig. 7, in 15 which the space between the members of the duplicator is greater than the length of the spindle, a downwardly extending spring member 28, analogous to the spring 26, is provided, secured to the top of the duplicator, which is designated 29. The same form 20 of spindle shown in Fig. 6 may be used in connection with the type of duplicator a portion of which is shown in Fig. 7.

It is obvious that my improved spindle 25 may not only be used in connection with various forms of duplicators, but also with machines and apparatus intended for various other purposes, indeed it may be usefully employed wherever it is desirable to 30 provide a spindle or roller which is required to be easily and quickly reversed end for end for any purpose whatever and still in either position be adapted to be rotated to roll up material stored thereupon or for 35 any other reason.

The advantages of my invention will be 40 obvious from what has been above set forth concerning its construction and mode of operation. I do not limit myself to the exact 45 construction shown and described, as it will be evident that various departures might be made therefrom, without departing from the spirit and scope of my invention.

Having thus described my invention, what 45 I claim as new and desire to secure by Letters Patent is as follows:

1. In a spindle, the combination with a

tube adapted to have rolled or stored thereon a duplicating film or the like and provided at each end with a chuck-engaging member; of a shaft shorter than said tube and extending longitudinally therethrough and slideable therein, whereby only one end of said shaft may always project from said tube and form a bearing pin upon which 50 that end of the spindle may rotate, whereby said spindle is adapted to be interchangeably reversed end for end, substantially as herein set forth.

2. In a spindle, the combination with a 60 tube adapted to have rolled or stored thereon a duplicating film or the like and provided at each end with a chuck-engaging member; of a shaft extending longitudinally therethrough and slideable therein, whereby one 65 end only of said shaft may project from said tube when placed in position and form a bearing pin upon which that end of the spindle may rotate, the entire remaining portion of said shaft being contained within 70 said tube; whereby said spindle is adapted to be interchangeably reversed end for end, substantially as herein set forth.

3. In a duplicator, the combination with a frame having on one side a bearing and 75 on the other side a chuck; of a spindle comprising a tube adapted to have rolled or stored thereon a duplicating film or the like and provided at each end with a chuck-engaging member adapted to engage with 80 said chuck, and a shaft extending longitudinally through said tube and slideable therein, whereby one end only of said shaft may project from said tube when placed in position and form a bearing pin adapted to 85 engage with said bearing in the frame and upon which that end of the spindle may rotate; whereby said spindle is adapted to be interchangeably reversed end for end substantially as herein set forth.

In witness whereof I have hereunto signed my name this 29th day of September, 1917.

ALBERT ISAACS.

It is hereby certified that in Letters Patent No. 1,377,584, granted May 10, 1921, upon the application of Albert Isaacs, of New York, N. Y., for an improvement in "Spindles for Duplicating-Machines and the like," errors appear in the printed specification requiring correction as follows: Page 2, line 18, for the numeral "28" read *128*, and line 20 for the numeral "29" read *129*; and that the said Letters Patent should be read with these corrections therein that the same may conform to the record of the case in the Patent Office.

Signed and sealed this 14th day of June, A. D., 1921.

[SEAL.]

WM. A. KINNAN,

Acting Commissioner of Patents.

Cl. 242—68.
